(57) **CLAIM**

The ornamental design for a display screen with a transitional graphical user interface for an emergency resource administration software, as shown and described.

DESCRIPTION

FIG. 1 is a front view of a first image of a display screen with a transitional graphical user interface for an emergency resource administration software;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a 10th image thereof;

FIG. 11 is a front view of an 11th image thereof;

FIG. 12 is a front view of a 12th image thereof;

FIG. 13 is a front view of a 13th image thereof, comprising solidly shaded areas that are part of the claimed design;

FIG. 14 is a front view of a 14th image thereof, comprising solidly shaded areas that are part of the claimed design;

FIG. 15 is a front view of a 15th image thereof, comprising solidly shaded areas that are part of the claimed design;

FIG. 16 is a front view of a 16th image thereof;

FIG. 17 is a front view of a 17th image thereof;

FIG. 18 is a front view of an 18th image thereof;

FIG. 19 is a front view of a 19th image thereof;

FIG. 20 is a front view of a 20th image thereof;

FIG. 21 is a front view of a 21th image thereof;

FIG. 22 is a front view of a 22th image thereof;

FIG. 23 is a front view of a 23th image thereof;

FIG. 24 is a front view of a 24th image thereof;

FIG. 25 is a front view of a 25th image thereof;

FIG. 26 is a front view of a 26th image thereof;

FIG. 27 is a front view of a 27th image thereof;

FIG. 28 is a front view of a 28th image thereof;

FIG. 29 is a front view of a 29th image thereof;

(Continued)

FIG. 30 is a front view of a 30th image thereof; and, FIG. 31 is a front view of a 31th image thereof. The broken lines in the drawings depict portions of the display screen that form no part of the claimed design. The appearance of the transitional image sequentially transitions between the images shown in FIGS. 1-31. The process or period in which one image transitions to another image forms no part of the claimed design.
